United States Patent Office.

WILLIAM HENRY WINSLOW AND ERVING WINSLOW, OF BOSTON, MASSACHUSETTS.

Design No. 3,184, dated August 25, 1868.

DESIGN FOR TRADE-MARK.

The Schedule referred to in these Letters Patent and making part of the same.

TO ALL WHOM IT MAY CONCERN:

Be it known that we, WILLIAM HENRY WINSLOW, of Boston, in the county of Suffolk, and State of Massachusetts, and ERVING WINSLOW, also of Boston, aforesaid, have invented and designed a new and original Trade-Mark, of which the following is a full and exact description, reference being had to the accompanying drawing, making a part of this specification.

The design represents an open hand A, enclosed within a circle, B, in which there are, at intervals, open spaces C.

What we claim, and desire to secure by Letters Patent, is—

The design for a trade-mark, herein set forth and shown.

W. HENRY WINSLOW,
ERVING WINSLOW.
